UNITED STATES PATENT OFFICE

CHARLES A. MOORE, OF EDINA, MINNESOTA

REFRIGERATOR

Application filed January 26, 1931. Serial No. 511,285.

My invention relates to improvements in refrigerators, particularly, though not exclusively, for domestic purposes, an object of the invention being to provide a self-ventilating structure of the present character, which is simple and relatively inexpensive in construction.

Another object of the invention is to provide a refrigerator of the present character, in which fresh air is gravitated into the refrigerating chamber by means of a conduit so disposed therein as to be affected by the refrigerating medium within the structure and in which the air of highest temperature and of highest relative humidity, at the upper portion of the chamber, is compressed to the outside through an egress opening in the upper portion of the refrigerator structure.

A further object of the invention is to provide a refrigerator as above in which the ingress conduit is disposed within said egress opening, under which construction there is but one ventilating opening formed in the refrigerator structure.

An additional object of the invention is to provide simple and effective means in association with said ingress conduit and egress opening for localizing and collecting any accumulation of moisture that may be caused in the vicinity of the egress opening.

With the foregoing and other objects in view, which will appear in the following description, the invention resides in the novel combination and arrangement of parts and in the details of construction hereinafter described and claimed.

In the drawing, Figs. 1 and 2 are vertical sectional views of a refrigerator embodying my invention, Fig. 1 being taken as on the line 1—1 of Fig. 2 and Fig. 2 being taken as on the line 2—2 of Fig. 1, and Fig. 3 is a horizontal sectional view taken as on the line 3—3 of Fig. 1.

The illustrated embodiment of my invention includes the usual box-like cabinet A comprising a bottom 10, ends 11, front 12 with doors 13 therein, back 14 and top 15, said cabinet structure having an inner lining 16 suitably insulated as at 17. The interior of the cabinet A constitutes a chamber

B for provisions and, of course, contains a suitable refrigerating medium such as the conventional refrigerating unit indicated in dotted lines at 18.

In adapting the cabinet to the ventilating means embodied in the present invention, a single opening 19 is formed in the top 15 of the cabinet. An upright air ingress conduit 20, suitably supported within the chamber B as by means of brackets 21, is projected at its upper end through said opening 19. In external diameter, the conduit 20 is considerably smaller than the internal diameter of the opening 19, said opening being lined with a sleeve 22, which extends above the top of the cabinet and forms a passageway for the egress of air from the chamber B about the conduit 20. Mounted on said conduit 20 is a hood 23 for the upper end of the sleeve 22. An annular pan 24 for catching the drip from this hood 23 encircles the sleeve 22, said pan being fitted with a suitable drain pipe, as at 25.

It is desirable, though not necessary, that the conduit 20 and refrigerating medium 18 be relatively closely disposed. Air within the conduit 20, being cooled therein, descends from the outside to the bottom of the chamber B and thence commingles with the air internally circulating by gravity in said chamber. Due to the compression in the chamber, which is built up by the gravitating ingress of air thereto through conduit 20, and by the respiration of the perishables in the chamber, the vitiated air of highest temperature and highest relative humidity in the upper stratum of the chamber B has free egress from the chamber through the sleeve 22. This air, thus displaced from the chamber, is intercepted by the hood 23 and deflected downwardly before it becomes free in the atmosphere of the room in which the refrigerator is located. Under such conditions as will cause the accumulation of moisture upon the hood 23, the pan 24 will serve to catch the drip from said hood and the drain pipe 25 will conduct the water away from said pan.

If desired, the conduit 20 and sleeve 22 may be extended through the wall of the room in which the refrigerator is located so that

the chamber B is brought into communication with the outdoor atmosphere. In such event, when such atmosphere is of a lower temperature than that of the chamber B, the ingress ⁵ of air to the chamber takes place through the sleeve 22 and the egress of air through conduit 20, all by gravity.

Among the several advantages residing in the present improvement, it is to be noted that ¹⁰ the ventilation of the refrigerator is accomplished alone by gravity; that it is necessary to form but a single opening in the cabinet for both ingress and egress of air thereto; that any objectionable accumulation of moisture ¹⁵ at the egress passageway is eliminated; that the ventilating equipment is exceedingly simple, inexpensive and easy to install; that this equipment is readily arranged to suit different constructions and that it occupies a limit- ²⁰ ed amount of usable space within the refrigerating chamber.

Changes in the specific form of my invention, as herein disclosed, may be made within the scope of what is claimed without departing from the spirit of my invention. ²⁵

Having described my invention, what I claim as new and desire to protect by Letters Patent is:

1. In a refrigerator, a cabinet enclosing a ³⁰ provision chamber, a refrigerating medium within said chamber, an upright conduit within the chamber leading downwardly thereinto from the outside, for the gravitating ingress of air therethrough to the chamber, ³⁵ said cabinet having an egress opening in the upper portion thereof through which air from the corresponding portion of the chamber is compressed to the outside.

2. In a refrigerator, a cabinet enclosing a ⁴⁰ provision chamber, a refrigerating medium within said chamber, a conduit leading downwardly from the outside into the cabinet structure and opening at its lower end into said chamber, said conduit being affected ⁴⁵ by said refrigerating medium and causing the gravitation of fresh air into said chamber, said cabinet having an egress opening in the upper portion thereof through which air from such portion of said chamber is compressed ⁵⁰ to the outside.

In testimony whereof I affix my signature.
CHARLES A. MOORE.
